No. 715,897.

Patented Dec. 16, 1902.

E. W. STREED.

BEVEL SQUARE.

(Application filed June 20, 1902.)

(No Model.)

Fig. 1.

UNITED STATES PATENT OFFICE.

ERIC W. STREED, OF MINNEAPOLIS, MINNESOTA.

BEVEL-SQUARE.

SPECIFICATION forming part of Letters Patent No. 715,897, dated December 16, 1902.

Application filed June 20, 1902. Serial No. 112,428. (No model.)

To all whom it may concern:

Be it known that I, ERIC W. STREED, a citizen of the United States, residing at Minneapolis, in the county of Hennepin and State 5 of Minnesota, have invented certain new and useful Improvements in Bevel-Squares; and I do hereby declare the following to be a full, clear, and exact description of the invention, such as will enable others skilled in the art to 10 to which it appertains to make and use the same.

My invention has for its object to provide a bevel-square of improved construction; and to this end it consists of the novel devices and combinations of devices hereinafter 15 described, and defined in the claim.

The invention is illustrated in the accompanying drawings, wherein like characters indicate like parts throughout the several views.

20 Figure 1 is a plan view, with some parts broken away, showing my improved bevel-square. Fig. 2 is a side elevation of the same, some parts being broken away. Fig. 3 is a section on the line $x^3 x^3$ of Fig. 1, and Fig. 25 4 is a section on the line $x^4 x^4$ of Fig. 3.

The character a indicates the head of the square, and the character b indicates the blade thereof. The head a is bifurcated or slit, as shown at a' , to afford a seat for the blade b . 30 One prong of the bifurcated portion of the head a is made shorter than the other and is extended by a case-section or housing c , the flange c' of which is rigidly secured to the short prong of said head by screws or other 35 suitable devices.

Working within the casing c is a relatively large gear f and intermeshing pinion f' , the former of which is rigidly secured to the pivoted end of the blade b by screws f^2 or other 40 suitable devices. A pivot is afforded for the gear f and blade b by a clamping-bolt g , which works loosely through the hub of said gear and is screwed into the hub h of a thin plate k' , which is secured by screws or other devices to the long prong of the bifurcated end 45 of the head a , as best shown in Fig. 3. The clamping-bolt g is preferably provided at its outer end with the shouldered thumb-piece g' , which bears against the outer face of the 50 case c . When the clamping-bolt g is tightened, it springs the prongs of the head a toward each other and tightly clamps the piv-

oted end of the blade b against the long prong of the head a and tightly pinches the hub of the gear f between the wall of the case c and 55 the nut or hub k , thus securely holding said gear and blade in whatever position they may be set.

The character m indicates a thin metal plate which is secured to the case c or at 60 least held against rotation with respect thereto and serves to exclude dust from the interior of said case. This dust-guard or plate m completely covers the pinion f' , but works loosely in an annular groove or notch cut in 65 the gear f .

The pinion f' is rigidly secured to a short shaft f^3 , which extends through and is journaled in the wall of the case c , as best shown in Fig. 3. At its outer end the shaft f^3 is 70 provided with a dial p , which preferably works in a shallow closely-fitting seat formed in the outer face of the case c . This dial is graduated to indicate degrees, but not, however, actual degrees of angular movement of said 75 dial. To illustrate, the gear f is four times the diameter of the pinion f' , and consequently if the said gear f and the blade b be moved through an arc of ninety degrees the pinion f' and dial p will be given four times 80 as much rotary movement—that is, will be given a complete rotation. Now, as ninety degrees is the greatest movement of the blade b which it is necessary to indicate, the dial p is graduated in multiples or fractions of 85 ninety degrees. In this way any slight movement of the blade b and gear f will be multiplied four times on the dial p , and thus, as is evident, a much greater accuracy is obtained 90 than would be obtained by placing the dial on the gear f or where it would receive direct movement from the blade of the square. For co-operation with the dial p a pointer of some suitable character is provided. Such a pointer may be afforded by a simple radial mark p' , 95 placed on the outer face of the case c adjacent to said dial, as shown in Fig. 1. Of course it is not necessary that the relation of four to one be maintained between the gears f and f' , but it is important in all cases that the rotary movement of the dial p be materially greater than that of the blade b . It will also be understood that the so-called 100 "dial" might be marked on a relatively fixed

part and the so-called "pointer" be made to move over the same. This would be simply a reversal of the construction shown and clearly within the scope of my invention. In this 5 construction it is of course very important that the coöperating gears or gear and pinion be accurately cut, so that they will work without slack or play.

In the head of the square I preferably place 10 a level-hub *t*, which adapts the head of the square for use as a level. The level is a valuable adjunct to the device, as it enables any desired angle to a horizontal to be indicated by the device. This especially adapts the 15 square for use in laying out stairs.

What I claim, and desire to secure by Letters Patent of the United States, is as follows:

The combination with the head *a*, bifurcated at *a'*, of the case *c* secured to one prong

of said head *a*, the plate *k'* secured to the 20 other prong of said head *a* and provided with the hub *k*, the clamping-bolt *g* working through the wall of said case *c* and screwed into said hub *k*, the large gear *f* loosely mounted on said clamping-bolt, the blade *b* secured 25 for angular movements with said gear *f*, the pinion *f'* mounted within said case and meshing with said gear, the graduated dial *p* meshing with said pinion *f'*, and a pointer *p'* on the exterior of said case *c*, said parts operating substantially as described.

In testimony whereof I affix my signature in presence of two witnesses.

ERIC W. STREED.
